UNITED STATES PATENT OFFICE.

ERNEST FISCHER, OF SALEM, OREGON.

GRAVITATING HINGE.

Application filed July 31, 1926. Serial No. 126,327.

This invention relates to gravitating hinges, and has more particular reference to hinges of this kind particularly adapted for the hanging of horizontally swinging doors and like closures so that when the latter are opened, they will be automatically returned to closed position.

The primary object of the present invention is to provide a gravitating hinge of the above kind which is extremely simple and durable in construction as well as efficient in operation.

A further object is to provide an improved form of gravitating leaf hinge which may be cheaply and easily constructed as well as readily placed into use.

Still another object is to provide a gravitating hinge which is reversible or adaptable for use with either doors which swing open in one direction or with doors which swing open in the opposite direction, simply by inverting the hinge from position as used in connection with one of the doors in order to adapt the hinge to the other or an oppositely swinging door.

A still further object is to provide a reversible gravitating hinge of the above kind wherein the hinge leaves are disposed to normally extend from the hinge pintle in the same direction so that the hinge is adapted to oppositely swinging doors by mere inversion of the hinge, and means for changing the normal relation of the hinged leaves so that the same will normally extend in opposite directions for adapting the hinge to double acting doors or doors which swing open in two or opposite directions.

Another object is to provide simple and effective means for accelerating the return of a leaf of the hinge to normal position for thereby accelerating closing of the door.

A further object is to provide an improved gravitating hinge having simple and effective means for causing the upper leaf to rise when swung relative to the lower leaf during the opening movement of the door, whereby said upper leaf will automatically swing backwardly and lower when the door is released, for thereby automatically effecting closing of the door.

Other objects will become apparent as the nature of the invention is better understood, and the same consists in the novel form, combination and arrangement of parts hereinabove more fully described, shown in the accompanying drawings and claimed.

In the drawings, wherein like reference characters indicate corresponding parts throughout the several views,

Figure 1 is an elevational view, partly broken away and in section, of one form of gravitating hinge constructed in accordance with the present invention, and with the upper leaf of the hinge swung from normal position to a position wherein a door hung by the hinge will be opened when swung to the left as indicated by the arrow;

Figure 2 is a view somewhat similar to Figure 1 with the hinge of the latter figure inverted for use in connection with a door which swings open to the right as indicated by the arrow;

Figure 3 is an enlarged horizontal section taken substantially upon line 3-3 of Figure 1;

Figure 4 is a view similar to Figure 3, taken upon line 4-4 of Figure 1;

Figure 5 is a fragmentary view partly in elevation and partly in section illustrating the manner of associating a spring with the pintle and a leaf of the hinge for accelerating return of said leaf to normal position and thereby accelerating closing movement of a door hung by the use of the hinge;

Figure 6 is a view partly in elevation and partly broken away and in section, of a modified form of gravitating hinge constructed in accordance with the present invention and with the leaves thereof in normal position;

Figure 7 is an elevational view of a still further form of reversible gravitating hinge constructed in accordance with the present invention;

Figure 8 is an edge elevational view thereof looking toward the left of Figure 7;

Figure 9 is an enlarged horizontal section taken substantially upon line 9-9 of Figure 8;

Figure 10 is a fragmentary view of the hinge shown in Figure 7 with the leaves adjusted so as to normally point or extend in opposite directions whereby the hinge is adapted for use in connection with double acting doors or doors which swing open in opposite directions; and

Figure 11 is a view partly in elevation, and partly broken away and in section, of a further modified form of the present invention adapted for use in connection with double acting doors or doors which swing open in opposite directions.

Referring more in detail to the drawings,

the form of the invention shown in Figs. 1 to 4 inclusive embodies an elongated cylindrical pindle 5 having a plurality of similar uniformly spaced and inter-twining right hand spiral grooves 6 in one end portion thereof, and a plurality of similarly related left hand spiral grooves 7 in the other end portion thereof, said grooves terminating in slightly spaced relation at their inner or adjacent ends at the intermediate portion of the pindle, and terminating short of the ends of the pindle at the outer ends thereof. A hinge leaf 8 has a rigid vertical barrel 9 along one edge, and this barrel 9 is freely rotatable and longitudinally slidable upon one end portion of the pindle 5, while a similar hinge leaf 10 is provided with a rigid barrel 11 along one vertical edge which is freely rotatable and slidable longitudinally upon the other end portion of the pindle 5.

The barrel 9 is provided with one or more key elements engageable in one or more of the right hand grooves 6 of the pindle 5, whereby when the leaf 8 is disposed uppermost as shown in Fig. 1 and attached to the door with the leaf 10 disposed lowermost and fixed to the door frame, the door will be carried upwardly with the leaf 8 when the door is opened, the leaf 8 moving from its normal dotted line position of Figure 1 during such opening movement of the door, to the full line position of Figure 8, and turning in the direction of the arrow *a* of Figure 1. In a like manner, the barrel 11 of the hinge leaf 10 is provided with one or more key elements engaging in one or more of the left hand spiral grooves 7 in the other end portion of the pindle 5, whereby when the hinge is inverted end for end from the position of Figure 1 to the position of Figure 2 with the leaf 8 arranged lowermost and attached to the frame and the leaf 10 arranged uppermost and attached to the door, said door may be swung open to the right, and simultaneously carried upwardly with the leaf 10 on the portion of the pindle 5 which is now uppermost, at which time the leaf 10 will swing in the direction of the arrow *a'* from its normal dotted line position to the raised full line position. It is thus apparent that the hinge may be readily inverted for being adapted to a door which swings open to the left, or to a door which swings open to the right, and in each case the door and the leaf which is arranged uppermost will automatically tend to gravitate to the normal position wherein the door and upper leaf are lowered and the door is closed. Thus, as soon as the door is released when opened, it will automatically be returned to closed position as is well known in the art. It will be noted that in both instances the leaves normally extend in the same direction from the pindle. However, means is provided, as will later become apparent, whereby the hinge leaves may be changed in relative normal positions so as to normally extend in opposite directions from

the pindle whereby this same hinge may be adapted for mounting a door which is of the double acting type or adapted to swing open in either direction. In such use of the invention, assuming that the leaf 8 is disposed uppermost, said leaf 8 will be raised on the pindle when the door is swung open to the left as in Figure 1, while the pindle will thread upwardly out of the barrel 11 of the leaf 10 when the door is swung open to the right or in the opposite direction. An inspection of the drawing will reveal the fact that this operation is inherent to the structure without illustrating in a view the normal position of the hinge leaves so as to project normally in opposite directions from the pindle.

As the manner of providing key elements for the barrels of both leaves is alike, description of one will suffice. As shown with respect to the leaf 10, such manner of providing the key elements consists in providing the inner end of the barrel 11 with a plurality of transverse openings, in each of which is freely positioned a bearing ball 12 forming a key element and engaging in the adjacent spiral groove 7 of the pindle 5. These bearing balls or key elements 12 are retained in place by means of a sleeve 13 fitted over the inner end of the barrel 11 and about the elements 12 as shown clearly in Figure 4. Obviously, by removing the sleeve 13 and the balls 12, the leaves may be normally positioned to extend in the same direction and the balls 12 then engaged in the grooves 7, or the balls or key elements 12 may be removed and the leaves arranged to normally extend in opposite directions and the balls then again positioned in place, the sleeve 13 being again placed upon the end of the barrel 11 to retain the balls in position in either case. As the openings of the barrel in which the balls 12 are disposed are uniformly spaced apart, each will register with a groove 7 irrespective as to whether or not the leaves 8 and 10 extend in the same direction or in opposite directions when normally disposed in adjacent relation completely upon the end portions of the pindle. With this construction either leaf may be changed in relation to the other leaf, and access to the key elements or balls of either leaf barrel may be readily had upon removal of the associated sleeve 13 in case it is desired to do so for removal, repair or adjustment. Naturally, by the use of bearing balls 12 as key elements, a minimum amount of frictional resistance is offered to the turning and sliding movement of the barrels on the end portions of the pindle.

The inner end portion of each leaf is separated from the adjacent end portion of its barrel by the provision of a vertical or longitudinal slot 14 of a length at least equal to the length of the sleeve 13, so that the latter may be placed upon the end portion of the barrel as mentioned. In order to removably retain

the sleeve 13 in place, the outer wall of the slot 14 is formed with a notch 15 in which is adapted to seat an external annular flange 16 provided upon the sleeve 13. The flange 16 is provided with a transverse groove 17 adapted to be registered with the adjacent end of the hinge leaf so that the sleeve 13 may be placed upon the end of the barrel to an extent to position the flange 16 coincident with the notch 15. When this is done the sleeve 13 is rotated so as to bring the groove 17 out of registry with the notch 15 and cause a portion of the flange 16 to enter the notch 15 so that the sleeve 13 is removably retained in place. Naturally, the sleeve 13 may then be removed by turning it until the groove 17 registers with the adjacent end of the hinge leaf and the flange 16 is thereby disengaged from the notch 15, at which time the sleeve 13 may be freely slid off of the end of the barrel. The outer ends of the barrels may be closed by suitable ornamental plugs as indicated at 18 so as to give the hinge a finished appearance, and the leaves 8 and 10 are provided with the usual openings 19 so that screws or the like may be passed therethrough for attaching the leaves respectively to the door and the door frame.

The inner end of the barrel of each hinge leaf is provided with a pair of oppositely facing ratchet teeth which present a pair of substantially diametrically opposed and oppositely facing flat shoulders 20 respectively adapted to engage opposite sides of the opposite ends of a cross pin fixed in and extending transversely through the intermediate portion of the pintle 5, when the adjacent end of said pintle is completely threaded into the barrel provided with said shoulders 20, whereby the threading of the pintle into said barrel is limited to the proper distance by the ends of the pin 21 engaging the shoulders 20 immediately prior to the time when the key elements or balls 12 of the said barrel reach the inner ends of the associated spiral grooves. In this way, the key elements 12 do not engage the ends of the grooves for limiting the inward threading of the pintle into the barrel, and damage of the key elements or balls 12 as well as wearing thereof and the grooves from this source is thereby prevented. Naturally, the shoulders 20 upon one hinge leaf barrel will face oppositely from those on the other hinge leaf barrel so that the same function is obtained in connection with each leaf, the pin 21 being of sufficient diameter to engage the shoulders 20 of the barrel of either or both leaves. Further, this construction permits the upper leaf to swing in either direction when the hinge is employed with double acting doors. For instance, with the parts positioned as shown in Figure 1 except that the upper leaf 8 will be adjusted to normally extend as in its full line position when lowered or normally disposed, swinging of the leaf 8 to the right for opening the door in one direction will result in the shoulders 20 of the barrel 9 engaging the ends of pin 21 and thereby causing the pintle 5 to turn in the barrel 11 and thereby thread upwardly out of the latter, whereas, upon swinging the leaf 8 to the left the ends of the pin 21 will engage the shoulders 20 of the barrel 11 so that the pintle 5 may not turn or thread further into the barrel 11 and the barrel 9 will accordingly thread upwardly on the upper end of the pintle 5 allowing the door to swing open in the opposite direction. In either operation a raising of the door is effected so that the door will automatically gravitate to closed position when released.

The swinging of the upper leaf of the hinge backwardly to normal position for accelerating closing of the door may be accomplished in a simple and effective manner as illustrated in Figure 5, such an arrangement being desirable in some instances involving the hanging of exceedingly heavy doors which cause an excessive amount of friction to be set up between the relatively movable parts of the hinge. As shown in Figure 5 this is accomplished by threading one end of a bolt 22 into an end of the pintle 5 so that the bolt is fixed to the pintle coaxially of the latter with its inner end freely extending into the adjacent end of the barrel of the adjacent hinge leaf. In the illustrated instance, the leaf 8 is the one which is arranged uppermost, and a conoidal compression spring 23 formed of a spiral strip of resilient metal is placed on the bolt 22 with its larger lower end impinging against the adjacent upper end of the hinge barrel 9 and with its smaller upper end bearing against the head on the upper or outer end of the bolt 22. With this construction the hinge leaf is swung to the left from normal position and in so doing, its barrel 9 will travel upwardly on the pintle 5 so as to place the spring 23 under compression as the door associated with the leaf 8 moves to open position. Naturally, when the door is released the spring 23 will supplement the gravitating action of the hinge by its tendency to return to its normal expanded condition, and the closing movement of the door will be accelerated by reason of the spring 23 tending to force the leaf 8 to swing backwardly and lower to its normal position. The use of a conoidal compression spring enables the use of a relatively short bolt 22 by reason of the coils of the spring nesting one within the other when placed under compression.

The form of the invention shown in Figure 6 is substantially the same as that shown in Figures 1 to 4 inclusive except that the lower end of the pintle 5^a is not provided with spiral grooves and is removably secured in the barrel 11^a of the lower leaf 10^a by threading the lower barrel closure plug 18^a onto a threaded

stem 24 rigid with the lower end of the pintle 5^a as shown. With this construction the key elements or balls 12 are not provided for the barrel 11^a but will naturally be provided for the barrel 9 of the upper leaf, and the hinge will at all times be used with the leaf 10^a secured to the door frame and the leaf 8 attached to the door so as to adapt the latter to swing open to the left as indicated by the arrow α'' .
10 Naturally this form of hinge may be constructed in right and left hand types, the type shown being of the left hand type or the type for doors swinging open to the left. In constructing the right hand type of hinge the construction will be exactly the same except that the barrels will be provided upon the opposite or other vertical edges of the leaves and the spiral grooves in the upper end of the pintle 5^a will be right hand grooves instead of left hand grooves as shown in the form disclosed. Naturally, in this single acting form of the hinge shown in Figure 6, the use of the elements 20 and 21 is unnecessary, and if desired, the bolt 22 and spring 23 may 20 be associated with the upper end of the pintle 5^a and the barrel 9 of Figure 6 for accelerating closing of the door.

The form of hinge shown in Figs. 7 to 10 inclusive includes an elongated cylindrical pintle 5^b upon the opposite end portions of which are respectively rotatably and slidably disposed the barrels 9^b and 11^b of the leaves 8^b and 10^b respectively. The barrel of each hinge leaf in this form of the invention is provided with a V-shaped cam slot, the portions of which extend in inwardly diverging relation, whereby, when the hinge is operatively disposed, the cam slot of the upper leaf will be inverted with the portions in downwardly diverging relation while the portions of the cam slot in the lower leaf barrel will be disposed in upwardly diverging relation. Each end portion of the pintle 5^b is provided with a laterally projecting stub shaft upon which is journaled an anti-friction roller 26 arranged to move in the adjacent cam slot 25 of the associated leaf barrel. Each stub shaft and anti-friction roller thus forms a key element which co-operates with a cam groove 50 so that when the upper leaf is swung on the pintle it will also be caused to rise thereon until such roller engages an end of the cam slot in the upper leaf barrel, whereupon the pintle will be caused to turn causing the other roller 26 to rise in the cam slot of the lower leaf barrel to an end of such latter slot, the lower end of the pintle at the same time rising out of the barrel of the lower leaf. This permits full opening of a door in one direction as indicated by the dotted line position of the upper leaf in Figure 7, wherein the door has opened by swinging to the left as indicated by the arrow α'' . By dispensing the leaves to point or extend to the left instead of to normally extend to the right as shown

by full lines in Figure 7, the same opening movement of the door is permitted, with the door swinging in the opposite direction or to the right. Either hinge leaf may be disposed uppermost in either instance of use of this form of the hinge, it being merely necessary to have the leaves extend to the left when the door is adapted to open to the right, and to have the leaves extend to the right when the door is adapted to open to the left. As shown, 70 the leaves of the hinge normally extend in the same direction from the pintle when the hinge is adjusted for use with doors which only swing in one direction in opening. In such arrangement the stub shafts project at 80 the same side of the pintle, and the cam slots are provided in corresponding sides of the hinge leaf barrels. In order to adapt the hinge for use in connection with double acting doors or doors which are adapted to swing open in either direction, it is necessary to provide means for adjusting the leaves so that they will normally project in opposite directions from the pintle, and for this purpose one or both of the stub shafts carrying the 90 rollers 26 may be removable and reversible. For instance, each stub shaft may consist of a bolt 27 removably threaded in a transverse opening of the pintle adapted for insertion from either side of the pintle as shown in Figure 9. Thus, in adapting the hinge for double acting doors, the bolt 27 constituting the lower stub shaft associated with hinge leaf 10^b may be removed and inserted from the left hand side of the pintle as seen in Figure 7, 100 which will result in positioning the lower leaf so as to normally project or extend to the left of Figure 7 or in an opposite direction from that in which the upper leaf 8^b extends. By making both stub shafts in the 105 nature of removable and oppositely positionable bolts, either hinge leaf may be adjusted relative to the other hinge leaf to secure the normal positioning of the leaves whereby one extends in an opposite direction from the other. In such arrangement, one stub shaft will of course project from one side of the pintle while the other stub shaft will project from the opposite side of the pintle instead of having both of the stub shafts project from the same side of the pintle as shown in Figure 7. This change in the positioning of the stub shafts and the hinge leaves is clearly 110 illustrated in Figure 10. In all instances, the lower leaf is attached to the door frame while the upper leaf is attached to the door, and it will of course be apparent that the stub shafts and rollers form key elements which cooperate with the cam slot for causing the upper leaf to rise on the pintle when said upper leaf 120 is swung from normal position.

In the form of the invention shown in Figure 11 there are three leaves 8^c, 28 and 10^c arranged in super-imposed relation or one above another, the upper leaf being adapted for at- 125

tachment to the door, the lower leaf being adapted for attachment to the door frame, and the intermediate leaf being adapted to simply extend between the door and the door frame without being attached to either. As shown, the leaves 28 and 8^c are connected by pintle means indicated generally at 29 so as to conjointly form a hinge substantially as illustrated in Figure 6 with the pintle grooves 10 of left hand pitch, and the pintle associated with barrels at the left hand vertical edges of the leaves 28 and 8^c. Further, the leaves 28 and 10^c are connected by pintle means generally indicated at 30 along their opposite vertical edges so as to conjointly form another gravitating hinge construction of the type shown in Figure 6 with the spiral grooves of the latter pintle of right hand pitch. Thus, a double acting gravitating hinge is provided 15 in which the upper leaf is attached to an edge of a door by threading screws forwardly through the apertures of the upper leaf, and in which the lower leaf 10^c is attached to the frame by threading screws rearwardly 20 through the apertures of said lower leaf. With a door mounted in this manner it may be swung to the left of Figure 11 as indicated by the upper arrow, at which time the upper leaf will rotate about the pintle of the means 25 29 and rise on said pintle. On the other hand, the door may be swung open to the right of Figure 11 as indicated by the lower arrow, at which time the intermediate leaf 28 will swing about the pintle of the means 30 and 35 rise on such pintle. When swinging the door open to the left the leaf 28 will remain stationary resting flatly against the door frame, while when the door opens by swinging to the right the pintle means 29 and the upper leaf 40 8^c will swing together with the leaf 28 and the door about the pintle of the means 30. In either instance the door is caused to rise by means which allows the door to automatically 45 gravitate and simultaneously swing to closed position when released. The pintle means 29 and 30 are similar in construction and correspond to the pintle means of the hinge shown in Figure 6 except that the grooves of the pintle 29 are of opposite pitch from those of 50 the pintles 5^a and 30. The manner of providing the key elements or balls 12 in the hinge construction of Figures 1 to 4 inclusive is utilized also in the construction of Figures 6 and 11 as will be apparent. 55 From the foregoing description it is believed that the construction and operation as well as the advantages of the several forms of the invention will be readily understood and appreciated by those skilled in the art. 60 Naturally, the bolts 22 and spring 23 may be associated with the pintle and a leaf of any desired one of the different forms of hinges shown in a manner similar to that generally indicated in connection with the form of hinge shown in Figure 1.

Minor changes may be made without departing from the spirit and scope of the invention as claimed.

Having thus described my invention, I claim:—

1. A gravitating hinge comprising a vertical pintle, a pair of hinge leaves having rigid vertical barrels respectively rotatably and slidably fitted upon the opposite end portions of said pintle, and means associated with the pintle and the barrels of the leaves to cause one leaf to rise when swung in one direction with the other leaf fixed and disposed lowermost, and to cause said other leaf to rise when swung in the opposite direction with said one leaf fixed and disposed lowermost, said means including a member normally arranged to permit the uppermost leaf to normally occupy a lowered position pointing in the same direction as the other leaf, whereby the hinge may be adapted to a door opening one-way in one direction by arranging one leaf uppermost and pointing in one direction or adapted to a door opening one-way in the opposite direction by arranging the other leaf uppermost and pointing in the opposite direction, said member being adjustable from normal position to a position to cause the uppermost leaf to stop when lowered so as to point in the opposite direction from the other leaf whereby the hinge may be adapted to a door adapted to swing open in opposite directions.

2. A gravitating hinge comprising a vertical pintle having a spiral groove in one end portion thereof, a hinge leaf having a rigid barrel in which the other end portion of the pintle is mounted, a second hinge leaf having a rigid barrel horizontally rotatable and vertically slidable on the first named end portion of the pintle, said barrel of the second leaf having a transverse opening, a bearing ball loosely arranged in said transverse opening and engaged in the spiral groove of the pintle, and means associated with said barrel of the second leaf to removably hold the bearing ball in place, an end portion of the second leaf being separated from the adjacent end portion of the barrel thereof by a vertical slot, and said bearing ball holding means comprising a sleeve removably slidably fitted on said adjacent end portion of the barrel over the bearing ball.

3. A gravitating hinge comprising a vertical pintle having a spiral groove in one end portion thereof, a hinge leaf having a rigid barrel in which the other end portion of the pintle is mounted, a second hinge leaf having a rigid barrel horizontally rotatable and vertically slidable on the first named end portion of the pintle, said barrel of the second leaf having a transverse opening, a bearing ball loosely arranged in said transverse opening and engaged in the spiral groove of the pintle, and means associated with said barrel

of the second leaf to removably hold the bearing ball in place, an end portion of the second leaf being separated from the adjacent end portion of the barrel thereof by a vertical 5 slot having a notch in the outer wall thereof, and said bearing ball holding means comprising a sleeve removably slidably fitted on said adjacent end portion of the barrel over the bearing ball and having an external annular 10 flange, said flange having a transverse slot to permit positioning of the sleeve with the flange thereof coincident with said notch whereby the flange will seat in said notch when the sleeve is partially rotated, for thereby 15 preventing sliding of the sleeve off of the barrel.

4. A reversible gravitating hinge comprising a vertical pintle having a plurality of inter-twining right hand spiral grooves in one 20 end portion thereof and a plurality of inter-twining left hand spiral grooves in the other end portion thereof, a hinge leaf having a rigid barrel horizontally rotatable and slid- 25 able longitudinally on said one end portion of the pintle, a key element carried by said barrel and engaging in a groove of said one end portion of the pintle, a second hinge leaf having a rigid barrel horizontally rotatable and slid- 30 able longitudinally on said other end portion of the pintle and a second key element carried by the barrel of the second leaf and engaging in a groove of said other end portion of the pintle, one of said key ele-

ments being normally arranged to engage one of the grooves in one end portion of the pintle 35 for permitting the leaves to normally extend from the pintle in the same direction for adapting the hinge to doors opening one-way in either direction, said one key element being adjustable to engage in another of the 40 grooves in said one end portion of the pintle for changing the normal position of the leaves with the latter extending from the pintle in opposite directions whereby the hinge is adapted to doors which swing open 45 in opposite directions.

5. A gravitating hinge comprising a vertical pintle having a spiral groove in one end portion thereof, a hinge leaf having a rigid barrel in which the other end portion of the 50 pintle is mounted, a second hinge leaf having a rigid barrel horizontally rotatable and vertically slidable on the first named end portion of the pintle, said barrel of the second leaf having a transverse opening, a bearing ball loosely arranged in said transverse opening and engaged in the spiral groove of the pintle, and means associated with said barrel of the second leaf to removably hold the bearing ball in place, said ball holding means embodying a sleeve removably fitted on the 55 barrel of the second leaf and adapted to be turned into or out of interlocking engagement with the latter.

In testimony whereof I affix my signature.

ERNEST FISCHER.
